Int. Cl. D17—04

U.S. Cl. D56—1

FIG. 1

FIG. 2

FIG. 3

FIG. 4

FIG. 1 is a perspective view of a drumstick, showing my new design;

FIG. 2 is a side elevational view, the appearance being the same from all sides;

FIG. 3 is a view of the left end in FIG. 2; and

FIG. 4 is a view of the right end in FIG. 2.

A portion of the drawing figure is shaded to indicate an electrostatically applied flocking.

I claim:

The ornamental design for a drumstick, as shown and described.
